[57] ABSTRACT

Novel dioxathiocin carboxylic acids, esters, salts and amides, which reduce blood lipids in warm blooded animals, are useful in the treatment of hyperlipidemic states and possess anti-infective properties, are represented by compounds of the following formula:

Formula I

wherein each Y, Y', Z and Z' represent hydrogen, halogen such as chlorine, fluorine, bromine or iodine, or lower alkyl or from one to four carbon atoms; or each set of Y and Y' or each set of Z and Z' forms a naphthalene ring which may be unsubstituted or substituted with a substituent selected from a halogen atom such as chlorine, fluorine, bromine or iodine or lower alkyl of from one to four carbon atoms; W represents hydroxy, lower alkoxy of from one to four carbon atoms; or $-\text{NR}^1\text{R}^2$; R¹ and R² represent hydrogen or lower alkyl of from 1 to 4 carbon atoms and may be the same or different; or R¹ and R² taken together with the nitrogen atom to which each is attached form a saturated monocyclic heterocyclic group such as pyrrolidino, piperidino, morpholino, piperazino or N-(lower)-alkyl-piperazino.

DIOXATHIOCIN CARBOXYLIC ACIDS, ESTERS,
SALTS AND AMIDES

FIELD OF INVENTION

This invention relates to novel dibenzo[d,g][1,3,6]dioxathiocin, dinaphtho[2,1-d:1',2'-g][1,3,6]dioxathiocin, and dinaphtho[1,2-d:2',1'-g][1,3,6]dioxathiocin carboxylic acids, esters, salts, and amides which reduce blood lipids in warm blooded animals, are useful in the treatment of hyperlipidemic states and possess anti-infective properties.

SUMMARY OF THE INVENTION

The novel compounds of this invention are represented by the following formula;

Formula I

20

Formula III

25

Formula IV

30

In the above Formulas II, III, and IV each of Z, Z', Y, Y' and R³ represent hydrogen, halogen such as chlorine, fluorine, bromine or iodine, or lower alkyl of from one to four carbon atoms and W has the meaning defined hereinbefore.

35

DETAILED DESCRIPTION OF INVENTION

The most preferred compounds of this invention are represented by the following Formulas V and VI:

Formula V

Formula VI

45

50

55

60

wherein W has the meaning defined hereinbefore.

As examples of lower alkyl radicals that Y, Y', Z, Z', R¹, R², R³, and the N-(lower)-alkyl substituent on the piperizino ring which may be present in Formulas I-IV, may represent there may be mentioned, for example, methyl, ethyl, propyl, isopropyl, butyl and the like.

Formula II

As examples of compounds of this invention there may be mentioned, for example,

- 2,10-dichlorodibenzo[d,g][1,3,6]dioxathiocin-6-carboxylic acid,
 dinaphtho[2,1-d:1',2'-g][1,3,6]dioxathiocin-8-carboxylic acid,
 2,4,8,10-tetrachlorodibenzo[d,g][1,3,6]dioxathiocin-6-carboxylic acid,
 methyl 2,4,8,10-tetrachlorodibenzo[d,g][1,3,6]dioxathiocin-6-carboxylate,
 2,4,8,10-tetrachlorodibenzo[d,g][1,3,6]dioxathiocin carboxamide,
 ethyl 2,14-dimethyldinaphtho[2,1-d:1',2'-g]dioxathiocin-8-carboxylate,
 4,12-dibromodinaphtho[2,1-d:1',2'-g]dioxathiocin-8-carboxamide,
 3,13-diethyldinaphtho[2,1-d:1',2'-g]dioxathiocin-8-carboxylic acid,
 2,10-dichlorodinaphtho[1,2-d:2',1'-g]dioxathiocin-8-carboxylic acid,
 N,N-diethyl-5,11-dipropyldinaphtho[2,1-d:1',2'-g]dioxathiocin-8-carboxamide,
 2,14-difluoro-N,N-dipropylbenzo[d,g][1,3,6]dioxathiocin-6-carboxamide,
 3,9-diethylbenzo[d,g][1,3,6]dioxathiocin-6-carboxylic acid,
 ethyl 2,4,8,10-tetrapropylbenzo[d,g][1,3,6]dioxathiocin-6-carboxylate,
 1,11N,N-tetramethylbenzo[d,g][1,3,6]dioxathiocin-6-carboxamide,
 1-(dibenzo[d,g][1,3,6]dioxathiocin-6-carbonyl)piperidine,
 1-(2,10-dimethylbenzo[d,g][1,3,6]dioxathiocin-6-carbonyl)pyrrolidine,
 1-(2,10-dichlorobenzo[d,g][1,3,6]dioxathiocin-6-carbonyl)piperazine,
 1-(2,10-dichlorobenzo[d,g][1,3,6]dioxathiocin-6-carbonyl)-4-propylpiperazine,
 1-(2,10-dipropylbenzo[d,g][1,3,6]dioxathiocin-6-carbonyl)morpholine, and the like.

The novel compounds of this invention reduce blood lipids, particularly lipoproteins containing cholesterol and triglycerides in warm-blooded animals and are useful in the treatment of hyperlipidemic states such as are encountered in patients with cardiovascular diseases, especially atherosclerotic diseases that can result in heart failure and stroke. Also, the compounds of this invention possess anti-infective properties.

The compounds of this invention can be used in the form of pharmaceutical preparations which contain the novel compound suitable for oral or parenteral administration. The quantity of compound in unit dosage form can vary a wide range to provide from about 0.5 mg/kg to about 4 g/kg of body weight and preferably 1 mg/kg to 1 g/kg of body weight of the subject per day to achieve the desired effect.

To illustrate the utility of the compounds of this invention young male rats of the Wistar strain weighing initially about 170 grams were given free access to a diet to which the indicated amount of test compound was added. This diet was prepared by thoroughly mixing the compound with commercial PURINA CHOW¹ ('Trademark of Ralston Purina Company, St. Louis, Miss.). Groups of animals were given these diets for a period of 10 days. Control groups were given the same diet with no added drug. At the end of the treatment

period, all rats were bled by cardiac puncture and the plasma was analyzed for cholesterol and triglyceride content on a Technicon AUTOANALYZER² ('Trademark of Technicon Corporation, Tarrytown, N.Y. 5 10591.). The results are given in the following Table I.

TABLE I

Test Compound	Adminis- tered % in diet (a)	Con- sum- ed mg/ kg (a)	Plasma Choles- terol % (b)		Plasma Trigly- cerides % (b)

25 (a) Determined by measuring food consumption.

(b) Compared to untreated control rats in the same experiment.

Other compounds of this invention show comparable results when administered under similar conditions.

30 As antiinfectives, compounds of this invention when administered subcutaneously have been found to be effective in mice against certain types of viruses, for example, encephalomyocarditis; bacteria, for example *Staphylococcus aureus* and *Salmonella schottmuelleri*; and fungi, for example, *Candida albicans*.

35 The compounds of this invention are prepared by reacting one equivalent of a compound of the formula

Formula VII

or a salt thereof and at least two equivalents of dihaloacetate salt, for example, dichloroacetate salt, in a suitable solvent and in the presence of excess base to give dioxathiocin carboxylate salts of Formula VIII.

Formula VIII

The various symbols, Y, Y', Z and Z' in the above Formulas VII and VIII have the meaning defined as in Formula I, and M represents an inorganic salt forming radical.

Although the two or more equivalents of the dihaloacetate salt reactant can all be added at the start of the reaction, it is preferred that one equivalent of the dihaloacetate salt reactant is placed in the reaction mixture initially, and then at a period of from about 10 to 48 hours from the start of the reaction one or more equivalents of the dihaloacetate salt is added to the reaction mixture.

The salts of the thio-bisphenol or thio-bis-naphthol reactant and dihaloacetic acid are prepared in situ by addition of base. A variety of bases can be used such as, for example, potassium carbonate, sodium methoxide, potassium tert-butoxide, sodium hydroxide or potassium hydroxide. The preferred base is potassium carbonate, however, when substituted thio-bisphenols which have weaker acid values are used, it may be necessary to use a stronger base such as sodium methoxide or potassium tert-butoxide.

As examples of solvents suitable for use in the reaction there may be mentioned, for example, ethanol, n-propanol, isopropanol, n-butanol, tert-butanol, dimethylformamide, dimethylsulfoxide, water and the like. The preferred solvents are n-propanol and isopropanol.

The reaction mixture is heated to reflux with vigorous stirring for 10 to 120 hours, preferably 98 hours, after which the solvent is distilled off and replaced with water. The mixture is cooled and the product, a compound of Formula VIII, is collected, which may be converted to the acid by suspending it in water and acidifying the mixture with, for example, hydrochloric acid. The precipitate is collected and recrystallized from, for example, toluene or acetic acid to give the dibenzo [d,g][1,3,6]dioxathiocin-6-carboxylic acids, that is, compounds of Formula II wherein W represents hydroxy, and the dinaphtho[2,1-d:1',2'-g][1,3,6]dioxathiocin-8-carboxylic acids, that is, compounds of Formulas III wherein W represents hydroxy, or dinaphtho[1,2-d:2',1'-g][1,3,6]dioxathiocin-8-carboxylic acids, that is, compounds of Formula IV wherein W is hydroxy.

The corresponding lower alkyl esters may be prepared by esterification of the above mentioned acids with lower aliphatic alcohols by generally known esterification procedures.

The corresponding dioxathiocin carboxamides may be obtained by the action of ammonia, or an appropriate primary amine such as ethylamine or propylamine, or an appropriate secondary amine such as dimethylamine, diethylamine, piperidine, morpholine, N-methylpiperazine and the like, on the acid halide or the ester of the above mentioned dioxathiocin carboxylic acids. The ester derivative may be obtained by the procedure described hereinbefore, and the acid halide may be obtained by reacting the dioxathiocin carboxylic acid with thionyl halide, for example, thionyl chloride by generally known procedures.

The reactant thiobisphenols and thiobisnaphthols, that is, compounds of Formula VII are prepared by reacting, 2 moles of an appropriately substituted phenol or naphthol with 1 mole of sulfur dichloride in the presence of a Lewis acid and under conditions

generally employed for a Friedel-Crafts reaction.

EXAMPLES

Representative compounds of the invention and their preparation are illustrated in the following specific examples.

EXAMPLE 1

2,4,8,10-Tetrachlorodibenzo[d,g][1,3,6]dioxathiocin-6-carboxylic acid

15 50 g (0.141 mole) of 2,2'-thiobis(4,6-dichlorophenol), 36.2 g (0.282 mole) of potassium carbonate, 5.0 g (0.03 mole) of potassium iodide, 18.2 g (0.141 mole) of dichloroacetic acid and 500 ml of n-propanol were combined and refluxed with vigorous stirring for 48 hours after which 36.2 g (0.282 mole) of potassium carbonate and 18.2 g (0.141 mole) of dichloroacetic acid were added. The mixture was refluxed with stirring an additional 24 hours, then the solvent was removed by distillation being gradually replaced with water. The mixture was allowed to cool, and the precipitate was collected and washed with 500 ml of 2 percent aqueous potassium hydroxide. The solid was suspended in 1 liter of water to which was added hydrochloric acid until the mixture was acidic to litmus paper. The resulting solid was washed with water, dried and recrystallized twice from toluene to give 24 g of the desired product, M.P. 231°-233°C (dec.).

EXAMPLE 2

Methyl 2,4,8,10-tetrachlorodibenzo[d,g][1,3,6]dioxathiocin-6-carboxylate

To 500 ml of methanol containing 5 ml of concentrated sulfuric acid was added 20.0 g (0.05 mole) of 2,4,8,10-tetrachlorodibenzo[d,g][1,3,6]dioxathiocin-6-carboxylic acid, and the mixture was refluxed for 3 hours. Upon cooling the resulting crystalline product was recrystallized from acetone-methanol to give 16.8 g of the desired product, M.P. 154°-156°C.

EXAMPLE 3

Dinaphtho[2,1-d:1',2'-g][1,3,6]dioxathiocin-8-carboxylic acid

55 A mixture of 50.0 g (0.157 mole) of 1,1'-thiodi-β-naphthol, 87.0 g (0.628 mole) of potassium carbonate, 5.0 g (0.03 mole) of potassium iodide, 20.3 g (0.157 mole) of dichloroacetic acid and 600 ml of n-propanol was refluxed with vigorous stirring for 24 hours after which an additional 20.3 g (0.157 mole) of dichloroacetic acid was added. The mixture was refluxed with stirring an additional 64 hours, then the solvent was distilled off being gradually replaced with water. The mixture was cooled and the resulting precipitate was dried and recrystallized twice from toluene to give the desired product, M.P. 233°-238°C (dec.).

EXAMPLE 4

2,10-Dichlorodibenzo[d,g][1,3,6]dioxathiocin-6-carboxylic acid

Substituting an appropriate amount of 2,2'-thiobis(4-chlorophenol) for 2,2'-thiobis(4,6-dichlorophenol) in the procedure of Example 1, the desired product was obtained, M.P. 224°-227°C.

EXAMPLE 5

Methyl 2,10-dichlorodibenzo[d,g][1,3,6]dioxathiocin-6-carboxylate

Substituting 2,10-dichlorodibenzo[d,g][1,3,6]dioxathiocin-6-carboxylic acid for 2,4,8,10-tetrachlorodibenzo[d,g][1,3,6]dioxathiocin-6-carboxylic acid in the procedure of Example 2, the desired product was obtained, M.P. 196°-198°C.

EXAMPLE 6

n-Propyl 2,4,8,10-tetrachlorodibenzo[d,g][1,3,6]dioxathiocin-6-carboxylate

By the procedure of Example 2 only substituting n-propanol for methanol the desired product is obtained.

EXAMPLE 7

2,4,8,10-Tetrachlorodibenzo[d,g][1,3,6]dioxathiocin-6-carboxamide

A mixture of 2,4,8,10-tetrachlorodibenzo[d,g][1,3,6]dioxathiocin-6-carboxylic acid and excess thionyl chloride is refluxed for 2 hours after which the thionyl chloride is removed by distillation under reduced pressure affording the acid chloride. This acid chloride is slowly added to an excess of cold strong ammonia with stirring. The temperature of the reaction is kept below 15°C with an ice bath. The reaction mixture is diluted with water and the resulting precipitate collected to give the desired product.

EXAMPLE 8

By the procedure of Example 7, only substituting for ammonia, approximately a 10 fold excess of diethylamine, piperidine, morpholine, or N-methylpiperazine dissolved in approximately a two fold volume of water the following compounds are obtained:

N,N-diethyl-2,4,8,10-tetrachlorodibenzo[d,g][1,3,6]dioxathiocin-6-carboxamide, 1-(2,4,8,10-tetrachlorodibenzo[d,g][1,3,6]dioxathiocin-6-carbonyl)-piperidine, 1-(2,4,8,10-tetrachlorodibenzo[d,g][1,3,6]dioxathiocin-6-carbonyl)-morpholine, 1-(2,4,8,10-tetrachlorodibenzo[d,g][1,3,6]dioxathiocin-6-carbonyl)-4-methylpiperazine

By the procedure of Example 1 only substituting for 2,2'-thiobis(4,6-dichlorophenol) an appropriate amount of the phenols listed in Table 2 the respective products listed in Table 2 are obtained.

TABLE 2

Example No.	Phenol	Product
9	2,2'-thiodiphenol	dibenzo[d,g][1,3,6]di

10	2,2'-thiobis(4-fluorophenol)	oxathiocin-6-carboxylic acid
11	2,2'-thiobis(4-bromophenol)	2,10-difluorodibenzo[d,g][1,3,6]di
12	6,6'-thiodipseudocumeneol	oxathiocin-6-carboxylic acid
13	2,2'-thiobis(tetrachlorophenol)	1,2,3,4,8,9,10,11-hexamethyl-dibenzo[d,g][1,3,6]dioxathiocin-6-carboxylic acid
14	2,2'-thiobis(3,4,6-trichlorophenol)	1,2,3,4,8,9,10,11-hexachlorodibenzo[d,g][1,3,6]di
20		oxathiocin-6-carboxylic acid

By the procedure of Example 3 only substituting for 1,1'-thiodi- β -naphthol an appropriate amount of the naphthols listed in Table 3 the respective products listed in Table 3 are obtained.

TABLE 3

Example No.	Naphthol	Product
15	1,1'-thiobis(6-chloro-2-naphthol)	3,13-dichlorodinaphtho[2,1-d:1',2'-g][1,3,6]-dioxathiocin-8-carboxylic acid
16	2,2'-thiobis(4-chloro-1-naphthol)	2,14-dichlorodinaphtho[1,2-d:2',1'-g][1,3,6]-dioxathiocin-8-carboxylic acid
17	1,1'-thiobis(6-methyl-2-naphthol)	3,13-dimethyl-dinaphtho[2,1-d:1'2'-g][1,3,6]-dioxathiocin-8-carboxylic acid
18	1,1'-thiobis(6-tert-butyl-2-naphthol)	3,13-di-tert-butyl-dinaphtho[2,1-d:1',2'-g][1,3,6]-dioxathiocin-8-carboxylic acid

EXAMPLE 19

50 2,10-Dimethyldibenzo[d,g][1,3,6]dioxathiocin-6-carboxylic acid

By the procedure of Example 1 only substituting for 2,2'-thiobis(4,6-dichlorophenol) an appropriate amount of 2,2'-thiodi- β -cresol, the desired product was obtained, M.P. 198°-201° (dec.).

EXAMPLE 20

60 Methyl 2,10-dimethyldibenzo[d,g][1,3,6]dioxathiocin-6-carboxylate

By the procedure of Example 2, only substituting for 2,4,8,10-tetrachlorodibenzo[d,g][1,3,6]dioxathiocin-6-carboxylic acid, an appropriate amount of 2,10-dimethyldibenzo[d,g]fc[1,3,6]dioxathiocin-6-carboxylic acid the desired compound was obtained, M.P. 104°-106°C.

EXAMPLE 21

By the procedure of Example 7 only substituting for 2,4,8,10-tetrachlorodibenzo[d,g][1,3,6]dioxathiocin-6-carboxylic acid appropriate amounts of 1,2,4,8,10,11-hexamethylidibenzo[d,g][1,3,6]dioxathiocin-6-carboxylic acid, dibenzo[d,g][1,3,6]dioxathiocin-6-carboxylic acid and dinaphtho[2,1-d:1',2'-g][1,3,6]dioxathiocin-8-carboxylic acid and substituting excess dipropylamine, dissolved in a two fold volume of water, for ammonia the following compounds are obtained:

N,N-dipropyl-1,2,4,8,10,11-hexamethylidibenzo[d,g][1,3,6]dioxathiocin-6-carboxylic acid
 N,N-dipropylidibenzo[d,g][1,3,6]dioxathiocin-6-carboxamide,
 N,N-dipropylidinaphtho[2,1-d:1',2'-g][1,3,6]dioxathiocin-8-carboxamide.

I claim:

1. A compound of the formula

wherein each of Y, Y', Z, and Z' is selected from the group consisting of hydrogen, halogen, or a lower alkyl radical of from one to four carbon atoms; or each set of Y and Y' or each set of Z and Z' taken together with the aromatic ring to which each set is attached forms a naphthalene ring which may be unsubstituted or substituted with a substituent selected from a halogen atom, or a lower alkyl radical of from one to four carbon atoms; W is selected from the group consisting of hydroxy, a lower alkoxy radical of from one to four carbon atoms or $-NR^1R^2$ wherein each of R¹ and R² is selected from the group consisting of hydrogen or a

lower alkyl radical of from one to four carbon atoms, or R¹ and R² taken together with the nitrogen atom to which each is attached form a saturated monocyclic heterocyclic group selected from pyrrolidino, piperidino, morpholino, piperazino, or N-(lower)-alkylpiperazino.

2. A compound of claim 1 wherein W is selected from hydroxy or a lower alkoxy radical of from one to four carbon atoms.

10 3. A compound of claim 2 wherein each of Y, Y', Z, and Z' is selected from hydrogen, halogen or a lower alkyl radical of from one to four carbon atoms.

4. A compound of claim 3 which is 2,10-dimethylidibenzo[d,g][1,3,6]dioxathiocin-6-carboxylic acid.

15 5. A compound of claim 3 which is methyl 2,10-dimethylidibenzo[d,g][1,3,6]dioxathiocin-6-carboxylate.

6. A compound of claim 3 wherein each of Y, Y', Z, and Z' is selected from hydrogen or chlorine.

20 7. A compound of claim 6 which is 2,4,8,10-tetrachlorodibenzo[d,g][1,3,6]dioxathiocin-6-carboxylic acid.

8. A compound of claim 6 which is methyl 2,4,8,10-tetrachlorodibenzo[d,g][1,3,6]dioxathiocin-6-carboxylate.

25 9. A compound of claim 6 which is 2,10-dichlorodibenzo[d,g]e[1,3,6]dioxathiocin-6-carboxylic acid.

10. A compound of claim 6 which is methyl 2,10-dichlorodibenzo[d,g]ey[1,3,6]dioxathiocin-6-carboxylate.

30 11. A compound of claim 1 wherein each set of Z and Z' taken together with the aromatic ring to which each set is attached forms a naphthalene ring which may be unsubstituted or substituted with a halogen atom, or a lower alkyl radical of from one to four carbon atoms.

12. A compound of claim 11 wherein W is selected from hydroxy or a lower alkoxy of from one to four carbon atoms.

40 13. A compound of claim 12 which is dinaphtho[2,1-d:1',2'-g][1,3,6]dioxathiocin-8-carboxylic acid.

14. A compound of claim 1 wherein each set of Y and Y' taken together with the aromatic ring to which each set is attached forms a naphthalene ring which may be unsubstituted or substituted with a halogen atom, or a lower alkyl radical of from one to four carbon atoms.
